UNITED STATES PATENT OFFICE.

ALBERT J. RAY, OF FORT WORTH, TEXAS.

VALVE FOR EXPLOSIVE-ENGINES.

1,096,056.

Specification of Letters Patent.

Patented May 12, 1914.

Application filed February 27, 1912. Serial No. 680,352.

To all whom it may concern:

Be it known that I, ALBERT J. RAY, a citizen of the United States, residing at Fort Worth, in the county of Tarrant and State of Texas, have invented certain new and useful Improvements in Valves for Explosive-Engines, of which the following is a specification.

My invention relates to valves for explosive engines and to means for cooling the valve and to means for carbureting the explosive mixture, and the object is to provide a valve which has a conical or tapering surface so that the valve will be self grinding and self adjusting and which is internally air-cooled and to provide means whereby the mixture of explosives will be doubly carbureted or mixed and purified and to provide an improved oiling system in the valve-casing.

Other objects and advantages will be fully explained in the following description and the invention will be more particularly pointed out in the claims.

Reference is had to the accompanying drawings which form a part of this application and specification.

Figure 1 is a side elevation of an engine which is equipped with the improvements hereinafter set forth. Fig. 2 is a broken sectional view, showing the arrangement of the carbureting devices. Fig. 3 is a vertical section of a valve in position in its casing and showing the connection of the casing with an engine cylinder. Fig. 4 is a side elevation of the valve, showing the intake and exhaust groove. Fig. 5 is a horizontal section of the valve and its casing, taken on the line $x-x$ of Fig. 3. Fig. 6 is a vertical section of the valve, taken on the line $y-y$ of Fig. 8. Fig. 7 is a vertical section of the valve, taken on the line $z-z$ of Fig. 8. Fig. 8 is a plan view of the valve. Fig. 9 is a plan view of the valve, showing a variation in the intake and exhaust groove, there being two grooves instead of one groove.

Similar characters of reference are used to indicate the same parts throughout the several views.

An engine cylinder 1 is shown provided with a spark plug 2. A valve casing 3 is formed preferably integral with cylinder 1 and this casing is provided with an intake port 4 and an exhaust port 5. The casing 3 is closed at the upper end by a plug 6 and

the casing is provided with radiating flanges 7 for cooling purposes. The casing 3 is tapering and a tapering or conical valve 8 is mounted in the casing. The casing 3 has a tapering seat 9 for the valve 8. The valve 8 has a stem 17 provided with a tapering portion 10 which engages the seat 9. The valve 8 is a hollow valve, as shown in Figs. 5, 6, and 7, and the opening in the valve extends through the stem so that the interior of the valve has communication with the atmosphere. The air circulates within the valve during operation and cools the valve constantly. The valve seats by gravity and a toggle joint or connection 11 is provided for driving the valve. The stem has slots 12 by which the valve is engaged loosely by the toggle connection 11. The valve 8 has an intake and exhaust groove 13 which is tapered from the upper end downwardly and terminates at the seat 9. The groove 13 is flared at the upper end at 14 so that the charge of explosive mixture will have an easy approach to the engine cylinder 1. The inner wall 15 and the entire inner surface of the valve will be cooled by air from the atmosphere. The stem has perforations 16 in part 17 thereof for taking in air and explosive mixture, as hereinafter explained. A pipe 18 takes the heated explosive mixture out of the valve constantly and in this way the valve is kept cool. A groove 19 is formed around the interior of the casing 3 for oiling the valve. The valve 8 being rotated in its seat 9, oil will be carried to all parts of the exterior surface and consequently to all parts of the interior surface of the casing 3. The location of the groove 19 is advantageous because the interior of the casing will be supplied with a thin film of oil and the oil will be rubbed on the exterior over the entire length thereof. The groove 13 will be no hindrance to the spreading of the oil because the centrifugal force will make the oil cling to the interior surface of the casing.

The variation shown in Fig. 9 consists in a valve having two exhaust and intake grooves 20 instead of one groove 13. The valve would have to be driven only one-half as fast as a valve having one groove.

The valve is rotated by gearing shown in Figs. 1 and 2. A stub or hollow shaft 21 is connected to the valve stem 17 by the toggle joint 11. A bearing 22 is provided for the

2 stub or hollow shaft 21. The drawings show four cylinders and casings 3 and the casings 3 terminate with a cone-shaped seating portion 23. The valve stems 17 extend 5 through this seating portion 23 into a mixing chamber 24. The seats 23 rest in the top 25 of this chamber. The bearing 22 is mounted in the bottom of the mixing chamber, and has a flange which engages the in- 10 side of the bottom and a sleeve which projects through the bottom, making thus an elongated bearing for the stub shaft 21. A worm gear wheel 26 is mounted rigidly on each shaft 21 and these gear wheels 26 are 15 driven by gear wheels 27 which are rigidly mounted on a shaft 28 which is driven by any suitable gearing, as by gearing from the crank shaft (not shown). The return pipes 18 terminate in a secondary mixing chamber 29. Air and gasoline are introduced 20 into the mixing chamber 24 through the orifice 30 and the quantity of gasoline introduced into chamber 24 is regulated by the needle valve 31. Gasoline is contained in a tank 32 which has communication with the orifice 30 through the neck 33 and the needle orifice 34. A float valve 35 of the ordinary type in tank 32 regulates the height of 25 gasoline in the adjustable needle orifice. The amount of mixed air and gasoline is further controlled by the spring controlled gate 36 which is hingedly connected at the upper edge of the orifice 30 and is adapted to swing inwardly and outwardly about the projection 37 through which the gasoline is escaping. A bracket 38 is attached to the receiving nipple 39 and a rod 40 is pivotally connected to the gate 36 and extended through the bracket 38 and a spiral 30 spring 41 is placed on the rod 40 between the bracket 38 and a nut 42 by which the tension of the spring may be controlled to hold the gate 36 at different positions relative to the projection 37 for the purpose of increasing or decreasing the 35 vacuum within the chamber. The amount of air and gasoline is controlled at the entry through the orifice 30 as it passes into the mixing chamber 24. The mixture passes 40 through the perforations 16 up into the interior of the valve 8 where it is dried and is taken back through the pipe 18 into the secondary mixing chamber 29. The explosive mixture is fed from the tank 29 through 45 the conduit or intake pipe 43. A diluting valve 44 for the secondary mixing chamber is provided for admission of air to the explosive mixture as the latter is passing to the rotary feed valves. The stem 45 projects out of the casing and a spiral spring 50 46 is placed on the stem 45 between the casing and the nut 47, and the amount of air admitted is controlled by the tension of the spring 46 for the purpose of increasing the 55 vacuum, that is, for decreasing the inflow of

air and increasing the inflow of gasoline at will, or for decreasing the vacuum, that is, increasing the inflow of air and decreasing the inflow of gasoline. The mixture of air and gasoline is carbureted partly in the mixing chamber 24 and partly within the valve itself. The rapid evaporation of gasoline in the valve 8, or the rapid absorption of gasoline by the air in the valve 8, has an intense cooling action aside from the atmospheric circulation. The cold temperature which is created in the operation of carburetors and which is usually lost in carburetors is utilized for cooling the valve. 70 75

The pipe 43 is provided with a butterfly or throttle-valve 48 which is provided with a handle 49, and is used to control the amount of explosive mixture which is to be delivered to the intake port of the valve casing. The pipe 43 is connected to the intake manifold pipe 50 and port connections 51 connect pipe 50 to the valve casings 3. The port connections 51 connect the pipe 50 with the intake port 4 of each valve casing. Explosive mixture escapes from the 90 connection 51 through the intake port 4 into the groove 13 and from the valve casing through the port 52 into the engine cylinder 1. The exhaust pipe 53 is raised above the intake manifold and is to be connected to 95 the exhaust ports 5 of the valve casings 3 by port connections 54. The casings 3 and cylinders 1 may be cooled in any suitable manner, while the valves are cooled by the circulation of explosive mixture, as heretofore explained. 100

The circulation shown in Figs. 1 and 2 can be used to circulate either oil or water to cool the valves.

When the engine piston goes down on the 105 intake stroke, a vacuum is created in the pipe 50, pipe 43, pipes 18, and consequently in the interior of valves 8. This will cause air and gas to pass through orifice 30 into the mixing chamber 24 and thence through 110 perforations 16 into the interior of the valves 8. When gas passes through the intake port 5, it is received in the grooves 13 in the valves which form parts of the combustion chambers and thence passes through 115 the ports 52 which are always open or open all the time. The piston then returns on the compression stroke, the ports 5 being closed by the rotation of the valve. When the piston reaches the top center of its 120 stroke, ignition takes place. The piston is thus started on the working or power stroke. When the piston reaches the bottom center or lowest point of its stroke, its valve has been rotated until the exhaust begins to open 125 and the exhaust remains open until the piston rises to the top center or completes its cleanout stroke, thus being timed for a new intake.

Having fully described my invention, 130

what I claim as new and desire to secure by Letters Patent, is,—

1. A valve having a chamber therein and having a tapering seating portion and a groove in the outer surface tapering from the upper end thereof to the seating portion and a casing for said valve in communication with an engine cylinder and having intake and exhaust ports communicating periodically with the groove in said valve, the chamber in said valve communicating with the atmosphere and with a supply source of explosive mixture and with the inlet ports.
2. A rotary chambered conical valve having a tapered seating portion and a stem provided with an opening therethrough communicating with the chamber in said valve and said valve having a groove in the outer surface tapering from the upper end to said seating portion, a casing for said valve in communication with an engine cylinder and having intake and exhaust ports communicating at intervals with the groove in said valve and suitable pipes and valves connecting the chamber in said valve with a supply source of explosive mixture.
3. A casing in communication with an engine cylinder and having a tapered seat at the lower end and intake and exhaust ports in the side thereof and a chambered rotary conical valve seated in said casing and having a groove in the peripheral surface tapering from the upper end to the seat in said casing and passing said intake and exhaust ports and having a hollow stem communicating with the chamber therein and with the atmosphere and with a supply source of explosive mixture and with the inlet ports.
4. A casing in communication with an engine cylinder and having a tapered seat at the lower end and intake and exhaust ports in the side thereof and a chambered rotary conical valve seated in said casing and having a groove in the peripheral surface flared at the upper end and tapering from the flared portion to the seat thereof and having a hollow stem communicating with the chamber therein and with the atmosphere and with an oil tank and with the inlet ports.
5. A casing in communication with an engine cylinder and having a tapered seat at the lower end and intake and exhaust ports in the side thereof and a chambered rotary conical valve seated in and resting by gravity in said seat and terminating at the upper end at the communication of said casing with the engine cylinder and having a groove in the peripheral surface thereof tapering from the upper end to said seat and having a hollow stem communicating with the chamber therein and with the atmosphere and a connection for rotating the valve, said groove passing the intake and exhaust ports.
6. In an explosive engine provided with a casing in communication with an engine cylinder, a chambered rotary valve in said casing, a mixing chamber, means for controlling the admission of explosive mixture to said chamber, said valve having a hollow stem communicating with said chamber and with the interior of the valve, a secondary mixing chamber, a pipe leading from said secondary mixing chamber to said valve casing, and means for diluting the explosive mixture in its passage to the valve casing.
7. In an explosive engine provided with a casing in communication with the engine cylinder, said casing having intake and exhaust ports, a chambered valve rotating in said casing and having provision for controlling the intake and the exhaust to and from said cylinder through said casing, means for carbureting air within said valve, and means for conveying the explosive mixture from the interior of said valve to the intake port of said casing.
8. In an explosive engine provided with a casing in communication with the engine cylinder and provided with intake and exhaust ports, a chambered valve rotating in said casing and controlling the intake and exhaust ports and the admission of explosive mixture to and from said cylinder, and means for circulating explosive-forming elements and carbureting the same within said valve prior to the admission of the explosive mixture to the intake port of said casing.
9. In an explosive engine provided with a casing in communication with the engine cylinder and provided with intake and exhaust ports, a chambered valve rotating in said casing and controlling the explosive mixture to and from said cylinder and through said ports, means for circulating explosive-forming elements and carbureting the same within said valve prior to the admission of said elements to the intake port of said casing, and means for diluting the explosive mixture in transit from the interior of said valve to said intake port.
10. In an explosive engine provided with a casing in communication with the engine cylinder and provided with intake and exhaust ports, a chambered valve in said casing and controlling the intake and exhaust ports and the admission of explosive mixture to and from said cylinder, means for circulating explosive-forming elements and carbureting the same within said valve prior to the admission of the explosive mixture to the intake port of said casing, means for diluting the explosive mixture in transit from the interior of said valve to said intake port, and means for rotating said valve.
11. In an explosive engine provided with a casing in communication with the engine cylinder, and provided with intake and ex-

haust ports, a chambered gravity-seating valve in said casing for controlling the admission of explosive mixture to the intake port and to and from said cylinder, and for controlling the exhaust, means for circulating explosive-forming elements and carburizing the same within said valve prior to the admission of explosive mixture to the intake port of said casing, and means for 10 rotating said valve.

12. In an explosive engine provided with a casing in communication with the engine cylinder and having intake and exhaust ports, a gravity-seating hollow valve in said casing, a mixing chamber, said hollow valve having a hollow stem projecting in said chamber and having perforations for receiving mixture from said chamber, a stub shaft and a toggle-joint connecting said stub shaft 20 to said valve stem, means for driving said shaft, and means for conveying explosive mixture from the interior of said valve to the intake port of said casing.

13. In an explosive engine provided with a casing in communication with the engine cylinder and having intake and exhaust ports, a gravity-seating hollow valve in said casing, a mixing chamber, said valve having a hollow stem in communication with the 25 interior of the valve and with said mixing chamber, and having perforations for receiving mixture from said chamber, a stub shaft and a toggle-joint connecting said stub shaft to said valve stem, means for driving said shaft, means for conveying explosive 30

40 mixture from the interior of said valve to the intake port of said casing, a secondary mixing chamber, a pipe extending from the interior of said valve and terminating in said secondary mixing chamber, and means for diluting the explosive mixture in transit from said secondary mixing chamber to said intake port.

14. In an explosive engine provided with a casing in communication with the engine cylinder and having intake and exhaust ports, a chambered valve in said casing, a mixing chamber, said valve having a hollow stem projecting within said valve and terminating in said mixing chamber, and having perforations for receiving mixture from said mixing chamber, a stub shaft and a toggle-joint connecting the same to said valve stem, means for driving said shaft, means for conveying explosive mixture from the interior of said valve, a secondary mixing chamber receiving the mixture from said valve, means for conveying explosive mixture from said secondary mixing chamber to said intake port, and means for controlling the amount of explosive-forming elements to said first mentioned mixing chamber.

55 In testimony whereof, I set my hand in the presence of two witnesses, this 2nd day of February, 1912.

ALBERT J. RAY.
